CAN OPENING DEVICE

Harold B. Lloyd, Sioux City, Iowa

Application January 8, 1934, Serial No. 705,708

2 Claims. (Cl. 220—48)

My invention relates to a device for opening cans containing liquid contents.

An object of my device is to provide means attachable to a can to allow venting of the same.

5 A further object of my invention is to provide such means which will allow formation of such a vent without the necessity of auxiliary parts.

A further object of my invention is to provide such means so that a vent can be formed in the 10 can merely by the exertion of a firm downward hand or foot pressure.

A further object of my invention is to provide means associated with the vent means to conveniently form necessary air holes for providing 15 pressure to the liquid in the can.

A further object of my invention is to provide in a modified form, means for causing the puncturing means to act as a funnel.

A further object of my invention is to provide 20 all of the above mentioned means in a construction of great simplicity which can be manufactured at a very reasonable cost.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

30 Figure 1 is a plan view of a form of the device, Figure 2 is a sectional view of Figure 1 taken along the lines 2—2 of Figure 1,

Figure 3 is a further sectional view of Figure 1, Figure 4 is a plan view of a form of the device,

35 Figure 5 is a sectional view of Figure 4 taken along the lines 5—5 of Figure 5,

Figure 6 is a sectional view of Figure 4 taken along the lines 6—6 of Figure 4,

Figure 7 is a further sectional view of Figure 4,

Figure 8 is a plan view of a modification,

Figure 9 is a sectional view taken along the lines 9—9 of Figure 8,

Figure 10 is a further sectional view of Figure 8,

45 Figure 11 is a sectional view taken along the lines 11—11 of Figure 8,

Figure 12 is a modification,

Figure 13 is a sectional view taken along the lines 13—13 of Figure 12,

50 Figure 14 is a further sectional view of Figure 12,

Figure 15 is a sectional view taken along the lines 15—15 of Figure 12, and

55 Figures 16 to 18 illustrate a further modifica-

tion of my device, Figure 17 being a sectional view of Figure 16 along the lines 17—17.

The cans containing liquid such as oils and the like necessitate the use of auxiliary tools for 5 opening the same.

It is usually necessary to provide an opening wedge for distributing lubricating oils, which wedges are adapted to puncture the can top, providing a vent for the fluid therein. Various forms of these auxiliary tools are used as a separate 10 piece from the can itself.

It is the principal object to provide in my invention means attachable to the can, which means can be utilized to form a suitable vent for pouring the fluid in the can, and which means 15 can be made to form the vent through direct pressure, and without the necessity of using any outside devices or tools.

To attain this end, I provide efficient puncturing devices which are attached to the can at all 20 times, so that it is only necessary for the operator to use this device which is already in place for the puncturing operation, without the necessity of seeking any other tools.

I have used the character 10 to designate generally the top wall of the can, having side walls 11.

The puncturing member 12 is attached to the can top 10 by means of a small metal strip or wire 13, which member is soldered to the can at one extremity thereof, as at 14, and to the puncturing member at 15. The member 12 is enlarged at 13a, and includes the upwardly struck blades 16, the pair of which converge upwardly to the point 17 (see Figure 2). These blades 16 are struck by means of an expanded die or can be 35 attached in any suitable manner.

The arcuate extension 18 extends upwardly as shown in Figure 2 to about the position shown. A pair of legs 19 are bent upwardly from the member 12. A further arcuate member 20 is also 40 struck out of the member 12 as shown at the rear thereof.

Normally the device rests with the cutting edge upward as shown in Figure 2, and if desired, a metal or other guard, indicated by the dotted 45 lines 21 in Figure 1, can be used to protect the point or to protect other cans when shipping the same.

It will be understood, of course, throughout the descriptions that the points can be positioned 50 downwardly also, if desired.

In operation, the member 12 is reversed by twisting the wire 13 as shown in Figure 3 and brought down against the top of the can so that the legs 19 will bear thereagainst. First, the 55

member 12 is struck a sharp blow by means of the foot or the hand at about the point 22 causing penetration of the can top 10, leaving the opening 23 as shown in Figure 3 which provides 5 the necessary air opening for supplying air pressure to the contents of the can.

Next, the extremity of the member 12 is struck sharply in the same manner, and downwardly as indicated by the arrow 24. The member 12 will 10 then bend approximately at 25 and will pass through the top of the can in a shearing motion, since the point 17 will penetrate first and will provide an angular shearing effect.

The metal will be bent downwardly as at 26, 15 and this effect will be materially enhanced by means of the arcuate member 18, which will carry the metal with it, and will further insure a proper shearing effect, since it will absorb part of the strain. The contents of the can can then 20 be poured out through the opening 27 (see Figure 1), and it will not be necessary to remove the member 12, since the contents will be poured through this opening which is left therein.

The legs 19 provide a rigid piece from which to 25 operate the cutting blades so that the forward part of the cutting parts will not be bent, and will cut as a rigid member.

Figure 4 illustrates a modification in which the member 27 is channel shape as shown more clearly 30 in Figure 5, and which member is attached to the can at the points 28 and 29 by means of the fairly stiff wire 30. The member 27 terminates in the sharp point 28, which point is the extremity of the bevelled portions 29. The portions 29 are 35 sharpened to a cutting edge along their edges.

The member 27 includes the outwardly struck arcuate portion 31. In operation, the member 27 is placed vertically as shown in Figure 7, with the point against the inside edge of the can, and it 40 will be held in this position by virtue of the relative stiffness of the wire 30. It is then struck a sharp blow at the top 32 in the direction of the arrow 33. This drives the point downwardly into the can as shown in Figure 7, and the member 31 forces away the metal at 34, thereby, again, forming a suitable vent for pouring the liquid. When the can is tipped for pouring, the liquid will 45 be poured out through the channel shape member 27 as indicated by the arrow 35. It will be seen that this provides a natural pouring spout for the can.

Of course, if desired, the same point 28 can be 50 utilized to strike an air opening at first if necessary, and then the member 27 move to its proper position for forming the vent. In this case a longer wire 30 can be used.

A sharp blow with the foot or with a clenched hand is sufficient to cause penetration at the various points mentioned in this description, since 55 as soon as the fine point penetrates, the balance of the shearing operation is greatly facilitated.

Figure 8 shows a plan view of a modified form in which the strip 36 is soldered to the can at 37 and terminates in the broadened portion 38, which 60 includes the pair of upwardly struck legs 39. Securely affixed to the strip 36 at 38 is the solid triangular member 40 which tapers from the point 41 at the end thereof downwardly to the portion 38 of the strip 36, which point tapers outwardly to the extremity to the points 42 (see Figures 8 and 11) so that in effect the entire member is a solid triangle tapering to a common point.

A suitable guard 43 can be slipped over the 70 member 40, if desired. In use, the strip 36 is

bent over at 44 thereby reversing the cutting point so that it points downwardly.

The legs 39 will bear against the top of the can, and the device is struck downwardly in the direction of the arrow 45, thereby causing penetration of the point 41 and the resultant shearing along the top edge 46, which will cause an elongated vent to be formed. After striking and forming the vent, the extremity is bent upwardly as indicated by the dotted lines 47 so that the contents of the can can be poured out through the vent thus formed.

An air opening can be formed by striking in a suitable spot by twisting the portion 36, if such is desired. It will be observed that the bending 15 in this case when the member is struck occurs approximately above the legs 39 so the shearing member can function as a rigid piece.

A form similar to Figure 8 is illustrated in Figure 12. In this form, the member 48 is similarly 20 a solid piece, somewhat similar to the member 40 shown in Figures 8 to 11 inclusive, with the exception that it is formed into an integral piece with the base and terminates in the upturned leg 49. The leg 49 includes the somewhat rounded 25 portion 50.

It will be seen from the section in Figure 15 that the triangular shape of the member 48 extends to the bottom of the same as mentioned. The member 48 merges with the horizontal strip 30 51, and the shoulders 52 are provided, which shoulders are adapted to merge together with the tapered triangular surfaces 53. The reason for this will be apparent in the description of the 35 operation of the device.

The portion 51 of the device is attached at 54 to the fairly stiff wire 55 which is attached at 56 to the top of the can 10. This wire is stiff, and yet pliable enough to allow twisting or any positioning of the same.

In use the member 48 is bent over first to the position as shown by the dotted lines 57 in Figure 12 with the point down. It is then given a sharp blow at the end, which provides the air opening 58 (see Figure 14). It is then turned back to its 45 original position, and the strip 55 is twisted as at 62, so the point will again be downward, and the device will then be in the position as shown by the dotted lines 58 in Figure 14. The end of the member 48 is then struck in the direction 50 of the arrow 59 with a sharp blow. Then the point 60, which is made rather sharp, will penetrate through the metal and the shearing effect 55 will readily take place along the side of the triangle formed by the sides 53 of the device and the vent will be cut with the entire base 61 passing beneath the top surface of the can as indicated in Figure 14, so that the entire cutting point will pass through the top of the can forming 60 a large vent. As the downward motion of the point is taking place, the shoulders 52 will also have the tendency of spreading the metal apart, thereby increasing the size of the vent.

It will be noted that the upturned leg 49 provides a base for insuring a rigid structure, and 65 the rounded portion 50 will allow a convenient rolling motion thereon. It will be seen from this construction that the cutting device can be positioned at any desired place, and the cutting operation take place in a very convenient manner.

If such is desired, a depression can be formed as at 63 in the top of the can 10, which depression will receive the member 48, so that the point will not be too high up. This is merely an auxiliary construction, which can be used if neces- 75

sary so that the cutting member can be positioned normally at a lower level.

The form shown in Figure 16 includes the rigid member 64 which is attached at 65 to the wire 66, which in turn is attached to the can top at 67. The member 64 includes the upwardly bent portion 68 which terminates in the horizontal portion 69. The portion 69 includes the integral ears 70.

10 The cutting wedge 71 is received through its slot 72 by the vertical neck 68. The slot 72 is made fairly large so that the member 71 can be manipulated rather freely. A small raised portion 73 is formed on the portion 69. The member 71 tapers to the point 74, which point is the termination of the sides 75 which are bevelled to provide a cutting edge as shown.

15 The slot 76 is provided in the member 71 so that the ears 70 will slide therethrough in assembling the pieces.

20 A small point 77 can be provided as an integral extension of the member 64 at the rear therethrough. In operation the member 64 is raised as shown in Figure 18, and the member 71 is slipped up over the vertical neck 68 and the horizontal neck 69 until it reaches the shoulder formed by the ears 70.

25 It will be understood that the opening 72 is made large enough to pass over the slightly raised portion 73. When the device is raised, it is in the position as shown in the solid lines in Figure 18 with the point 74 ready for the cutting operation. A sharp blow is then struck in the direction of the arrow 78 approximately 30 at the position as shown, or if desired, the blow can be struck slightly rearwardly thereof. At the moment of impact, the point 74 will penetrate the top of the can 10, thereby shearing the same into a triangular vent, and the metal of the can will be carried down as indicated by the dotted lines at 79, and the device itself is also indicated by the dotted lines in this latter position. The metal is then cut away suitably so that a pouring vent is formed.

35 40 45 It will also be noted that the small point 77

will puncture a small opening at 80 to provide an air vent.

It will be understood, of course, that the striking surfaces can be rounded if desired in the case of striking with the hand, although a sharp blow struck on the member 64 will provide an efficient cutting operation.

10 It will now be seen that I have provided a device for opening a can which is attachable to the can and will provide means for readily forming a vent in the can, which allows formation of the vent without using any auxiliary parts, which is very simple in operation since it merely uses the function of direct pressure, and which means are provided in a construction of great 15 simplicity which can be manufactured at a very reasonable cost.

15 Some changes may be made in the construction and arrangement of the parts of my invention without departing from the real spirit and purpose of my invention, and it is my intention to cover by my claims any modified forms of structure or use of mechanical equivalents, which may be reasonably included within their scope.

20 I claim as my invention:

25 1. A can opening device comprising a flat shearing member positioned to lie against the upper can top, and including a piercing point at the extremity thereof, shearing surfaces tapering downwardly from said point, means for attaching the shearing member to the can, said shearing surfaces having an opening therebetween to allow pouring of a liquid therethrough.

30 2. A can-opening device comprising a flat shearing member positioned to lie against the upper can top, and including a piercing point at the extremity thereof, shearing surfaces tapering downwardly from said point, means for attaching the shearing member to the can, said shearing surfaces having an opening therebetween to allow pouring of a liquid therethrough, 35 said shearing member including upstanding legs positioned rearwardly from said shearing surfaces to provide a rigid cutting base for said shearing surfaces.

40 45 HAROLD B. LLOYD.
